UNITED STATES PATENT OFFICE

103,821

DESIGN FOR A TANK VEHICLE

Ralph L. Kuss, Joliet, Ill., assignor to Farrell Manufacturing Company, Joliet, Ill., a corporation of Illinois

Application February 15, 1936, Serial No. 61,192

Term of patent 14 years

To all whom it may concern:

Be it known that I, Ralph L. Kuss, a citizen of the United States, residing at Joliet, in the county of Will and State of Illinois, have invented a new, original, and ornamental Design for Tank Vehicle, of which the following is a specification, reference being had to the accompanying drawings, forming a part thereof:

Figure 1 is a side elevation of a tank vehicle showing my new design, the bumpers of said vehicle being omitted;

Figure 2 is a top plan view of the tank vehicle illustrated in Figure 1, the bumpers of said vehicle being omitted;

Figure 3 is an end elevation of the tank vehicle illustrated in Figure 1, the same looking toward the left as viewed in Figure 1;

Figure 4 is an end elevation of the tank vehicle illustrated in Figure 1, the same looking toward the right as viewed in said Figure 1 and showing the addition of a front bumper to the vehicle.

The dominant feature of the design resides in the tank portion of the vehicle.

I claim:

The ornamental design for tank vehicle, substantially as shown and described.

RALPH L. KUSS.
